(57) **CLAIM**

The ornamental design for a stand for solar panels, as shown and described.

DESCRIPTION

FIG. 1 is a front, right and bottom perspective view of a stand for solar panels showing my new design;

FIG. 2 is a rear, left and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view taken from circle 9 in FIG. 2;

FIG. 10 is a front, left and bottom perspective view of the stand for solar panels of FIG. 1;

FIG. 11 is a rear, right and bottom perspective view thereof;

FIG. 12 is another front, right and bottom perspective view thereof;

FIG. 13 is another rear, right and bottom perspective view thereof;

FIG. 14 is a rear, right perspective view of the stand for solar panels of FIG. 1 in an unfolded configuration;

FIG. 15 is a rear, left perspective view thereof in an unfolded configuration;

FIG. 16 is a front elevational view thereof in an unfolded configuration;

FIG. 17 is a rear elevational view thereof in an unfolded configuration;

FIG. 18 is a left side elevational view thereof in an unfolded configuration;

FIG. 19 is a right side elevational view thereof in an unfolded configuration;

FIG. 20 is a top plan view thereof in an unfolded configuration;

FIG. 21 is a bottom plan view thereof in an unfolded configuration;

FIG. 22 is a partial enlarged view taken from circle 22 in FIG. 11;

(Continued)

FIG. 23 is a front, right and bottom perspective view of the stand for solar panels of FIG. 1 in an unfolded configuration; and,

FIG. 24 is another front, right and bottom perspective view thereof in an unfolded configuration.

The dash-dash broken lines in the drawings depict the portions of the stand for solar panels which form no part of the claimed design.

The dot-dash broken lines in the drawings depict the boundaries of the partial enlarged views that form no part of the claimed design.
